(57) **CLAIM**

The ornamental design for a table, as shown and described.

DESCRIPTION

FIG. 1 is a left front perspective view of a table showing my new design;

FIG. 2 is a front perspective view thereof;

FIG. 3 is a left side elevational view thereof

FIG. 4 is a right side elevational view thereof; and,

FIG. 5 is a top view thereof.

The views of the table not shown form no part of the claimed design. The broken lines shown in the drawings represent a variety of environments, environments of varying lengths, or portions thereof and form no part of the claimed design. The fragmented depiction of surface ornamentation shown on the surfaces of the claimed design is understood to exist uniformly across that surface. The broken lines depicting hardware, feet, and ornamental elements represent environmental elements only and form no part of the claimed design.
